DESIGN FOR A FABRIC FOR CLOAKS, &c.

UNITED STATES PATENT OFFICE.

FRANK T. HOUSE, OF PORT CHESTER, NEW YORK, ASSIGNOR TO THE HAWTHORNE WOOLEN MILLS, OF GLENVILLE, CONNECTICUT.

DESIGN FOR A FABRIC FOR CLOAKS, &c.

SPECIFICATION forming part of Design No. 19,093, dated May 14, 1889.

Application filed April 10, 1889. Serial No. 306,719. Term of patent 3½ years.

To all whom it may concern:

Be it known that I, FRANK T. HOUSE, a citizen of the United States, residing at Port Chester, Westchester county, New York, have invented a new and original Design for Fabric for Cloaks, &c., of which the following is a specification, reference being had to the accompanying photograph, which forms a part of the same.

- 10 The invention relates to a design to be worked into or upon surfaces, such as cloakings or similar fabrics; and it consists in the novel configuration and grouping of figures herein specifically shown and claimed.
- 15 The accompanying photograph is a face view of a cloaking showing my new design.

My design consists of an ornamental figure somewhat crown-shaped in character, repeated so as to form a series of continuous parallel rows over the face of the fabric, and of a parallel-line ornamentation between these rows.

What I claim as new, and desire to secure by Letters Patent, is—

The design for fabrics, consisting of the design substantially as shown.

FRANK T. HOUSE.
